J. R. SANDAGE

HEATER

Filed July 25, 1925

Inventor:
Jacob R. Sandage
by Arthur H. Durand Atty.

UNITED STATES PATENT OFFICE.

JACOB R. SANDAGE, OF CHICAGO, ILLINOIS.

HEATER.

Application filed July 25, 1925. Serial No. 46,062.

This invention relates to heaters for use in houses, to heat the rooms thereof, and more especially those which are of a portable nature, such as oil and gas heaters, and electric heaters, which not only heat the immediately surrounding atmosphere, by radiation, but which also take in pure air and discharge it in heated condition as the result of the admixture therewith of the air heated inside of the heater, by immediate contact with the heating element, as well as by admixture therewith of any products of combustion, if the heater be of the kind, for example, that employs a gas or oil flame, whereby the volume of air is taken in at the bottom of the heater and is discharged in heated condition from the top or upper portion thereof.

Generally stated, the object of the invention is to provide a novel and improved construction of heater of the foregoing general character, having certain improvements in features of construction tending to increase the efficiency thereof, with a view to obtaining a greater heating capacity, for any given amount of fuel or electric current consumed in the operation of the heater.

It is also an object to provide certain details and features of construction tending to increase the general efficiency and the desirability of an air circulating heater of this particular character.

To these and other useful ends, the invention consists in the matters hereinafter set forth and claimed, and shown in the accompanying drawings, in which,—

Fig. 1 is a vertical section of an air circulating heater embodying the principles of the invention, showing the same equipped with a gas burner as the heating element thereof.

Fig. 2 is a horizontal section on line 2—2 in Fig. 1.

Fig. 3 is a detail or fragmentary view of a portion of the heater showing a different form of heating element,—that is to say, showing an electric coil as a substitute for the gas burner shown in Figs. 1 and 2.

As thus illustrated, the invention comprises a base 1 having a baffle plate 2 at the bottom thereof, spaced a distance from the floor by the legs 3 which support the base. The top of the base is provided with a central opening 4 to receive the lower end of the downwardly tapered air flue 5, and having a plurality of openings 6 arranged

in a circle surrounding the lower end of said flue. The cylindrical drum 7 has its lower end fixed on the base 1, as shown, and is provided at its upper end with a top 7 which extends inwardly to engage the upper end portion of the flue 5, as shown. Below the top 7, the said flue is provided with a plurality of openings 8, so that air passing upwardly through the openings 6, and through the space between the flue 5 and the drum 7, will enter the flue through the openings 8, as shown. The exposed upper end portion of the flue is provided with a plurality of larger openings 9, as shown, through which the heated air and products of combustion from the space 10 between the flue and the drum will escape into the atmosphere. It will also be seen that, with this construction, air passing upwardly around the edge of the baffle plate 2, as shown in Fig. 1, will enter the lower end of the flue 5 and pass upwardly and mingle with the air and products of combustion which enter through the openings 8, whereby a supply of pure and untainted air is taken upwardly through the heater, through the said downwardly tapered flue thereof, and is mixed with the air and products of combustion taken into the flue from the space or chamber 10, whereby a wholesome quantity of practically pure air in a highly heated condition is constantly discharged from the openings 9 into the atmosphere.

Any suitable means can be employed as the heating element. For example, as shown in Figs. 1 and 2, an ordinary gas burner 11 can be provided in the form of a ring encircling the flue, and provided with a valve 12 to control the flow of gas, whereby a gas flame of the required character will be produced in the chamber or space 10 to heat the air therein, by admixture with the gases or products of combustion, and by direct radiation from the flame, whereby the walls of the flue 5 will be heated to heat the air passing upwardly through the flue from the lower end thereof.

Of course, if desired, the electric heating element 13, in the form of a resistance coil of any suitable character, can be applied to the outer surface of the flue 5, and connected in circuit with a suitable source of current, thereby to electrically heat the air passing up through the heater.

It is also obvious that an oil heater (not shown) of any suitable character can be sub-

stituted for the gas heater shown and described, or that any other form of heating element can be employed substantially in the position and in the relative arrangement shown and described, without departing from the spirit of the invention.

It will be seen that by tapering the flue 5 downwardly, its sides overhang the burner 11, so that the flame of the latter will be 10 directed upwardly against the outwardly inclined outer surface of the flue, thus efficiently heating the latter. The heating element, of course, as stated, can be arranged in any suitable or desired manner, but is 15 preferably applied, regardless of the arrangement thereof, to the lower portion of the flue, so that the air entering the lower end of the flue will be heated almost immediately, whereby air entering the lower 20 end of the space outside of the flue will also be heated almost immediately upon entering at the base of the heater.

Thus the top plate 14 of the heater is imperforate, and with this arrangement the 25 heater has means for mixing and then laterally discharging the air and heated gases, immediately below said plate, and above the top of the space 10, so that all of the air entering the bottom of the heater is necessarily 30 discharged laterally from the top of the heater, and from the space immediately below the said top plate.

Without disclaiming anything, and without prejudice to any novelty shown and described, what I claim as my invention is:

1. In a heater for receiving air at the bottom thereof, and for heating the air therein, and for then discharging the heated air from the top thereof, the combination of a 40 body forming outer side walls for the heater, an open bottom flue extending upward therein, an imperforate top plate for the heater, with space between the outside of said flue and the inside of said body, the heater having means at the base thereof to admit air to the lower end of said flue, and also to the bot-

tom of said space, the flue having openings in the upper portion thereof below the top of said space to receive the heated air from the upper portion of said space, and the upper 50 portion of said heater having means disposed above the top of said space and below said top plate for commingling and for laterally discharging all of the air which enters the heater at the bottom thereof, and which 55 passes upward both inside and outside of said flue, in combination with a heating element applied to the lower portion of said flue, in position to heat some air directly and some indirectly through the wall of the 60 flue.

2. A structure as specified in claim 1, said heating element surrounding the outer surface of said flue, whereby air passing upwardly in said space is heated by direct contact with said heating element, and whereby pure air is heated in the flue and then mixed with the air entering the upper portion of the flue from said space.

3. A structure as specified in claim 1, in 70 combination with a baffle plate immediately below the lower end of said flue, spaced a distance therefrom, substantially as shown and described.

4. A structure as specified in claim 1, 75 said flue being tapered downwardly and having said heating element applied to the outer surface thereof, near its lower end, thereby to heat the air in the manner stated.

5. A structure as specified in claim 1, said 80 flue having an outwardly inclined side wall, so that the flue overhangs said heating element, the heating element being outside of said flue and disposed in position to apply the heat to the outer surface of said outwardly inclined wall of the flue, and the outer wall of the body being vertically disposed, so that said space tapers gradually upward.

Specification signed this 15th day of July, 90
1925.

JACOB R. SANDAGE.
